ANDREW J. REYNOLDS, OF STURGIS, MICHIGAN.

Letters Patent No. 75,648, dated March 17, 1868.

IMPROVEMENT IN MARINE PROPULSION.

The Schedule referred to in these Letters Patent and making part of the same.

TO ALL WHOM IT MAY CONCERN:

Be it known that I, ANDREW J. REYNOLDS, of Sturgis, in the county of St. Joseph, and State of Michigan, have invented a new and useful Improvement in Marine Propulsion; and I do hereby declare the following to be a full, clear, and exact description of the same, reference being had to the accompanying drawings, which are made a part of this specification.

My invention consists of a propelling-apparatus embodying the essential characteristics of a paddle-wheel and water-wheel; that is to say, the apparatus is of the rotating kind, is driven by the impingement or weight of water discharged from an elevated reservoir on to the buckets, and has paddles or blades, whose consequent action upon the buoying water propels the vessel.

The invention further consists in constructing the wheel of two independently movable parts, so that when it is desired to reverse the wheel, it can be effected by unclutching the one part from the other, when the weight of water in the buckets, in conjunction with the resistance offered to the paddles, serves to change the position of the buckets, the reservoir having a movable gate, whereby the point of discharge of the motive-water may be changed so as to cause the water to fall upon the opposite side of the wheel when the buckets are thus reversed.

Figure 1 is a sectional side elevation of a vessel with my invention applied.

Figure 2 is a transverse sectional view of the same, the propelling-device at one side being shown in section, and that at the other side in elevation.

Similar letters of reference represent corresponding parts in the two figures.

In the drawings, A may represent a vessel having a compound propelling-wheel at each side. As one of these compound propelling-wheels is but a duplicate of the other, the ensuing description will apply to the wheel-work situated at either side of the vessel. B is an arbor, rotating in suitable bearings in the vessel. C C are two wheels, or annular side-pieces, whose hubs are fitted loosely upon the arbor B, and connect with the rims by radial arms. c c c are arms (see fig. 1) projecting at regular intervals from the rims of the wheels C, and slotted, so as to receive the blades or paddles C', which are firmly held in place. The wheels C C and paddles C', combined as above, constitute a paddle-wheel. The paddle-wheel C C C' encloses a water-wheel, D D D', which is made in two parts, with radial arms and hubs the same as C C; but the hubs of the parts D D are made to engage with splines, b, on the shaft B, so that the water-wheel is compelled to rotate with said shaft. The water-wheel is of somewhat smaller diameter than the paddle-wheel, but concentric therewith. The tails of the buckets D' of the water-wheel are attached by pivots, d, to the rims of the water-wheel, and pins, d', projecting from the opposite sides of the buckets D', midway between their mouths and tails, occupy slots, c', in the rims of the paddle-wheel. It will be seen that the pins d' have sufficient play in the slots c' to permit the buckets D' to vibrate on their pivots d to the extent of about one-fourth of a revolution. Hence, supposing the buckets to have their mouths properly presented to receive water at the left side of the wheel, as shown in fig. 1, the buckets must be vibrated as above described, so as to present their mouths in the reverse direction when it is desired to adapt them to receive water at the right-hand side of the wheel in order to reverse the motion. The reversal of the buckets is effected by retracting the clutch F, thereby disconnecting the water-wheel from the paddle-wheel, for when the wheels have been thus unclutched, the weight of the water in the buckets at the receiving side of the wheel is sufficient to cause the water-wheel to turn within, and in a reverse direction to the paddle-wheel, the extent of such reverse motion being determined by the play of the pins d' within the wheel and thereby adapted to receive water at the right-hand side of the wheel, and impart rotation to the paddle-wheel in a contrary direction to that in which they previously turned. As soon as the buckets G have slid into their new position, the water and paddle-wheels are locked together by the clutch F. The elevated reservoir G has sliding gates, G¹, one for the propelling-apparatus at each side of the vessel, whereby the water may be shut off at one of the outlets G², and allowed to flow through the other, according to the direction of the wheels' rotation, or prevented from flowing through either outlet when the propelling-mechanism is to remain at rest. The gate G¹ may be shifted from one position to another by hand, through the medium of the rack H, cogged segment H¹, connecting-rods H² H⁴, and lever H³, or any other suitable connections.

The reservoir G is constructed and supported in any suitable manner, and the effective power of the water

upon the wheels may be determined by the height of the reservoir or the size of the discharge-outlets. Water is pumped into the reservoir G by one or more double-acting steam pumps, I, discharging water into the reservoir at the opposite sides thereof through the pipes J J'.

The propelling-mechanism and pumping-engine are entirely independent of each other, so that the engine may be in full operation while the propelling and water-wheels are at rest; and though the converse is also true, it may not be expedient to have the propelling-wheels operate for any considerable length of time while the pump remains idle.

This mode of propulsion dispenses with the expensive and easily-impaired mechanism which is necessarily employed to connect the engine with the wheels under the common mode of propulsion. It also enables the vessel to be placed wholly under the control of the pilot, who may, by operating the clutch F through suitable connections, reverse the water-wheel so as to move the vessel backward or forward at will. Of course the gates may be made to enlarge or contract the reservoir's outlets, and the speed of the vessel is diminished or increased accordingly.

It will be seen that by connecting the buckets D' by the pins d' to the rim of the wheel C C, motion is imparted to the latter without being first communicated to and then transferred from the arbor B. This rim-connection relieves the wheels from strain, and effects an economical application of the power.

Having thus described my invention, what I claim as new herein, and desire to secure by Letters Patent, is—

1. A propelling-apparatus for vessels, acting upon the water in which the vessel floats, when driven by a water-wheel of any suitable construction.

2. The combination of the wheels C C and D D with the pivoted buckets D', substantially as and for the purpose set forth.

To the above specification of my improvement in marine propulsion, I have signed my hand, this seventh day of December, 1867.

ANDREW J. REYNOLDS.
